BOTTLE

Edwin C. Laudano, Matawan, N.J., assignor to Thatcher
Glass Manufacturing Company, Inc., New York, N.Y., a corporation of New York

Filed Oct. 11, 1961, Ser. No. 67,049

Term of patent 14 years

(Cl. D58—5)

FIGURE 1 is a side elevational view of a bottle, showing my new design, and in which the side not shown is the same as the side shown;

The dominant features of my design reside in the portion shown in full lines.

I claim:

The ornamental design for a bottle, substantially as shown and described.
